UNITED STATES PATENT OFFICE.

GOODWIN B. SMITH, OF PHILADELPHIA, PENNSYLVANIA.

VENDING MACHINE.

Application filed May 6, 1924. Serial No. 711,493.

My invention relates to vending machines.

An important object of the invention is to provide means for holding and displaying a plurality of articles of merchandise, of 5 different character, and to permit of the proper selection of the desired article, prior to the vending of the same.

A further object of the invention is to provide a vending machine of the above mentioned character, the operation of which is controlled by a single coin, which is compact in the arrangement of its parts and economical in the use of space, which is so constructed that access may be had to all of the pockets 15 at one time, for refilling, which has a relatively large article holding capacity whereby the machine has a large selection of articles, which is novel and interesting in appearance thereby effecting curiosity sales, which permits of the removal of the articles by the purchaser whereby its discharge does not depend upon gravity or mechanical means, which is so constructed that the merchandise offered for sale need only be placed in the 20 pockets of the drum to insure delivery to a proper point to be removed, and requires no special packing or wrapping, which is easy and convenient to operate, has a low cost of production owing to its shape and mode of 25 assembly, which has an exceptionally wide field of usefulness, and which is adapted for use in the selling of articles of different sizes by simply varying the shape or size of the pockets in the drums, to receive the articles.

Other objects and advantages of the invention will be apparent during the course of the following description.

In the accompanying drawings forming a part of this specification, and in which like numerals are employed to designate like parts throughout the same,

Figure 1 is a side elevation of a vending machine embodying my invention,

Figure 2 is a horizontal transverse section 45 taken on line 2—2 of Figure 1,

Figure 3 is a transverse vertical section taken on line 3—3 of Figure 1,

Figure 3^a is a fragmentary detail section through two of the adjacent pockets of the 50 drum, showing their mode of assembly,

Figure 4 is a vertical section taken on line 4—4 of Figure 3,

Figure 4^a is a detail section taken on line 4^a—4^a of Figure 5,

Figure 5 is a vertical section taken on line 55 5—5 of Figure 3,

Figure 6 is a perspective view of the closure element or door, and associated elements,

Figure 7 is a side elevation of a modified 60 form of the invention,

Figure 8 is a vertical section taken on line 8—8 of Figure 7, and,

Figure 9 is a vertical section taken on line 9—9 of Figure 8.

In the drawings, wherein for the purpose 65 of illustration is shown a preferred embodiment of my invention, the numeral 10 designates the front or body portion of the casing,

which may be formed of sheet metal, or any other suitable material. This body portion is 70

suitably detachably mounted upon a back 11. The body portion 10 of the casing is prefer- 75

ably rectangular, as the machine may be conveniently placed upon a support, such as a shelf, while not necessarily restricted to this 80

use. The body portion 10 is provided in its front face with an annular group of openings 13, through which the goods may be observed, and these openings are covered by a section or 85

sections of transparent material, such as glass, celluloid or the like.

Arranged within the casing is a rotatable 90 drum, embodying center disks 14, which are rigidly mounted upon a hub 15, rotatable upon a stud 16, which is rigidly attached to

the back 11. The center disks 14 have an inner ring 17, soldered or otherwise rigidly secured thereto. The numeral 18 designates 95

a rear ring, which is soldered upon the inner ring 17, and constitutes a radial continuation of the rear disk 14, and also forms a back 100

closure for the compartments or pockets to be described. Each pocket includes a section of sheet metal or the like, bent into a radial partition or wall 19, and a circumferential wall 20,

such circumferential wall having an in- 105

wardly offset portion at 21, providing a shoul- der, for receiving the free end of the circum- 110

ferential wall 20 of the succeeding pocket ele- 115

ment. The free ends of the circumferential 120

walls 20 are soldered within the shoulders 21, and thereby overlapping, and forming in effect a continuous ring. The rear edges of 125

these overlapping walls are soldered to the outer edge of the ring 18. The radial walls 19 130

directions. These elements therefore form vertical receiving and holding pockets 23, which correspond in number and arrangement to the openings 13, and 13' these two groups being concentric.

Means are provided whereby a selected compartment or pocket 23 may be brought into proximity to or registration with a delivery opening 13' in the casing, to permit of the removal of the desired article, under proper conditions, and this means is illustrated as comprising a gear 24, rigidly attached to the disk 14, at its center, and permanently engaging a larger gear 25, which is rotatably mounted upon the stationary back 11, as shown at 26. The gear 25 is turned by an outer gear 27, rigidly mounted upon a shaft 28, which shaft is attached to the back 11 and is rotatable thereon. The shaft 28 is turned by a crank 29, arranged forwardly of the casing 10, and this crank is adapted to pass through an opening 30 in the body portion 10, when the body portion is removed. It is preferred that the gear ratio is such that upon the half turn of the crank 29, the pockets will be advanced one step, that is the proper distance to bring the next pocket in alignment with the opening 13'.

Upon the inner side of the delivery opening 13' is a preferably reciprocating door or closure element 31, formed of metal or any other suitable material. This door may have peep holes or windows 32, which may be covered or uncovered with any suitable transparent material, in order that the article directly behind the door may be observed. This door is slideable within vertical guides or tracks 33, which are mounted upon the inner side of the front of the body portion 10. The door 31 carries a rib 34, extending longitudinally thereof, and this rib is adapted for coaction with notches 35, formed in the ring 17, which constitutes the bottom of the pockets, as will be more fully explained.

Pivottally connected with the reciprocating door 31, as shown at 36, is a pitman 37, which is pivottally connected with a crank 38. This crank is moved upwardly by a retractile coil spring 39. The crank 38 is moved downwardly by coin controlled mechanism 40, including an exterior hand crank 41. That is, upon the insertion of a proper coin into the coin controlled mechanism, the crank 41 is turned clock-wise for approximately one-quarter of a revolution, and its movement is then limited. The crank 38 is drawn downwardly for a corresponding distance, and the door 31 will be shifted to the lowered or opened position. As soon as the door is released, in a manner to be described, the spring 39 will return the door and associated elements to the closed position, the lever 41 of the coin controlled mechanism being returned to the upper position and locked against turning movement, whereby the door cannot be

again opened before the insertion of the coin.

The door 31 is provided with a depending L-shaped latch 42, adapted to ride downwardly upon the upper beveled end of a coacting spring catch 43, which moves out of its path of travel, and then springs in over it, with its straight face 44 engaging on top of the horizontal arm of the latch. This spring catch will now lock the door in the lowered position, until the spring catch is shifted inwardly to disengage with the latch, which is effected by means of a rod 45, having a button 46 secured to its outer end.

The operation of this form of the machine is as follows:

The compartments or pockets 23 are filled with articles to be vended, of different characters, and the purchaser can observe these different articles through the several openings 13 and 13'. By turning the crank 29, the pocket 23 containing the desired article, may be brought in registration with the opening 13', whereby this selected article may be removed when the door 31 is opened. The machine being thus adjusted, the coin is inserted in the coin controlled mechanism, and the crank 41 turned down for one-quarter of a revolution. When this occurs, the crank 38 moves down and the door 31 descends, whereby access may be had to the interior of the adjacent pocket 23. When this door descends, the latch 42 engages beneath the spring catch 43, and hence the door is locked in the open position. The drum cannot now be rotated, to bring other pockets into registration with the opening 13', since the upper portion of the rib 34 remains within the notch 35. When the door is in the uppermost or completely closed position, the lower end of this rib is removed from the notch 35, and hence the drum may be rotated to select the articles, but only when the door is completely closed. The side walls of the pockets are sufficiently foreshortened so that they will clear the rib 34, in the rotation of the drum. It will therefore be seen, that before the operator can select the article, the button 46 must be pressed, to release the door, so that it may be moved to the completely closed position, subsequent to which the article may be selected, and then the door opened to permit of the removal of the article.

In Figures 7 to 9 inclusive, I have shown a slight modification of the machine, which is designed as a machine to be positioned upon the wall. In this machine, the front casing member 47 is preferably cylindrical, and 48 is a back. This back is attached to a bar 49, having transverse ends 50.

The operating parts of the machine are identical with those of the first form of the invention, except as specified. The drum embodying the pockets 23 is the same. Instead of employing the gear 24, I employ a ratchet wheel 24', rigidly attached to the

back 14 of the drum, and this ratchet wheel is rotatable on the stud 16. The ratchet wheel is engaged by a pawl 51, carried by a lever 52, which is pivoted upon this stud. The 5 stud is attached to the bar 48. The extent of movement of the lever 52 is preferably such that when it is moved downwardly for its entire extent of travel, the drum is turned a distance of one pocket. The lever is 10 turned by means of a spring 53. The same coin controlled means is employed to operate the door, and the operation of all other parts of the machine are identical with those first described.

15 It is to be understood that the forms of my invention herewith shown and described are to be taken as preferred embodiments of the same, and that various changes in the shape, size, and arrangement of parts may 20 be resorted to, without departing from the spirit of my invention, or the scope of the subjoined claims.

Having thus described my invention, I claim:

25 1. A vending machine of the character described comprising, a casing having a delivery opening, a rotatable drum within the casing having a set of pockets and provided with notches, means to turn the drum, a 30 slideable closure element moving generally radially of the drum and having a longitudinally extending rib to engage within the notches of the pocket as the pockets are brought to the delivery opening, said rib 35 remaining within the selected notch until the closure element is shifted to a substantially completely closed position, and means to move the slideable closure element to the opened and closed positions.

40 2. In a vending machine, a casing having a delivery opening, a drum mounted to turn within the casing and having radial pockets to be moved into proximity to the delivery opening, a radially movable door slidably 45 mounted upon the casing to cover and uncover the delivery opening, a rib extending longitudinally of the door and rigidly mounted thereon and adapted to engage with a part of the drum to lock the same against 50 turning movement and to disengage the same when the door is moved to substantially the completely closed position.

55 3. In a coin controlled vending machine the combination of: a casing having a delivery opening, a drum rotatably mounted within said casing and having radial compartments adapted to be selectively registered with said delivery opening, a door vertically reciprocable in said casing for opening and closing said delivery opening, means 60 for selectively aligning said compartments with said delivery opening when said door is closed, means for moving said door to open position, locking means mounted on and rigid 65 with said door and engaging said drum to

lock the latter against rotation when said door is open, and means for moving said door to closed position to unlock said drum.

4. In a coin controlled vending machine the combination of: a casing having a delivery opening, a drum rotatably mounted within said casing and having radial compartments adapted to be selectively registered with said delivery opening, a door vertically reciprocable in said casing for opening and closing said delivery opening, means for selectively aligning said compartments with said delivery opening, means for moving said door to open position, and a locking projection mounted on and rigid with 70 said door and movable into engagement with said drum when the door is open to lock the drum against rotation when said door is open.

5. In a coin controlled vending machine the combination of a casing having a delivery opening, a drum rotatably mounted within said casing and having radial compartments adapted to be selectively registered with said delivery opening, a door vertically slidable 75 in said casing for opening and closing said delivery opening, intermeshing gears controlled by a crank for selectively aligning said compartments with said delivery opening when said door is closed, means for moving said door to open position, a rib mounted on said door and adapted to engage spaced recesses in said drum to lock the latter against rotation when said door is open.

6. In a coin controlled vending machine the combination of a casing having a delivery opening, a drum rotatably mounted within said casing and having radial compartments adapted to be selectively registered with said delivery opening, a door slidably mounted 80 in said casing for opening and closing said delivery opening, intermeshing gears controlled by a crank for selectively aligning said compartments with said delivery opening when said door is closed, means for moving said door to open position, a rib mounted on said door and adapted to engage spaced recesses in said drum to lock the latter against rotation when said door is open, and a spring controlled plunger for permitting said door 85 to be moved to closed position to unlock said drum.

7. In a coin controlled vending machine the combination of a casing having a plurality of radially disposed display windows and a delivery opening disposed at the top of said casing, a drum rotatably mounted within said casing and having a plurality of radially disposed compartments registering with the display windows of the casing, a door vertically reciprocable in said casing and normally closing said delivery opening, means for rotating said drum to align a selected compartment with said delivery opening, means for opening and closing said door, and 125 130

means carried by and rigid with said door and engaging said drum to lock the latter against movement when said door is open.

8. In a coin controlled vending machine the combination of a casing having a plurality of radially disposed display windows and a delivery opening disposed at the top of said casing, a drum rotatably mounted within said casing and having a plurality of radially disposed compartments registering with the display windows of the casing, a door vertically reciprocable in said casing and normally closing said delivery opening, means for rotating said drum to align a selected compartment with said delivery opening, means for opening and closing said door, locking means carried by and rigid with said door and engaging said drum to lock the latter against movement when said door is open, and means for closing said door to permit free rotation of said drum.

9. In a coin controlled vending machine the combination of a casing having a plurality of radially disposed display windows, and a delivery opening disposed at the top of said casing, a drum rotatably mounted within said casing and having a plurality of radially disposed compartments registering with the dis-

play windows of the casing, a door slidably mounted in said casing and normally closing said delivery opening, gears for rotating said drum to align a selected compartment with said delivery opening, means for opening and closing said door, a locking rib carried by said door and adapted to engage spaced notches in a peripheral wall of said drum to lock the latter against movement when said door is open, and means for closing said door to permit free rotation of said drum.

10. A vending machine comprising a casing having a plurality of radially disposed display windows and a door aperture, a drum rotatably mounted in said casing and having a plurality of article receiving compartments adapted to register with said display windows and selectively with said door aperture, a door mounted for vertical reciprocation in said casing for opening and closing said aperture, said door being adapted in its open position to engage said drum to lock the same against rotation and in its closed position to disengage said drum to permit free rotation of the latter within said casing, and means for opening and closing said door.

In testimony whereof I affix my signature.
GOODWIN B. SMITH.
